UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

THROW-OUT MECHANISM FOR PRINTING-PRESS DELIVERY.

Application filed May 18, 1923, Serial No. 639,858. Renewed January 10, 1928.

The principal object of this invention is to provide for throwing out from a delivery device a printed product or the like for inspection or any other purpose without lessening the full number of products contained in the bundles delivered by the delivery mechanism. This provides for rectifying the count so that the counting of the number of products in a bundle will remain accurate, although from time to time one of the products is thrown out and diverted from the bundle to which it would otherwise be delivered.

The invention also involves means whereby the throw-out device will be kept in inoperative condition ordinarily by very simple means and whereby when released by hand it will be prevented automatically from operating until the full number of products to make a complete bundle have been delivered, or at least started through the delivery mechanism, and then it will act automatically to divert one product and to prevent the counting of that product. Thus the number of products in each bundle is the same no matter whether one is thrown out or not. The invention also involves means for immediately restoring the throw out mechanism to its inoperative condition after a single product has been diverted by it and leaving it in its inoperative position until released thereby by hand.

Additional advantages and features of the invention will be described hereinafter.

Reference is to be had to the accompanying drawings, in which

Fig. 1 is an end elevation of a delivery mechanism provided with a preferred embodiment of this invention;

Fig. 2 is a sectional view taken just inside the frame of the machine and showing practically all the elements, except the shafts, in side elevation, and illustrating the position of the parts when the products are being fed through in the normal manner, and

Fig. 3 is a similar view showing the position when the throw-out device is acting to divert a printed product.

It is common to provide newspaper delivery mechanisms with a throw-out device for diverting a product from the delivery mechanism for inspection and similar purposes. It is also common to provide the delivery mechanism with means for separating the delivered products into bundles of fifty

each. This separation is performed in a simple way and permits the operators to take up fifty printed products at a time and there is no need of counting them. However, so far as I am aware, it has always been necessary to take a product thrown out for inspection out of one of the bundles so that that bundle would have only forty-nine products as delivered. This invention is designed to overcome that difficulty by providing for delivering uniform bundles of fifty each, or any other number desired, operative to produce that result, no matter whether the throw-out mechanism is operated or not.

The invention is shown as applied to a delivery mechanism having the usual folding rollers 1, delivery fans 2 and guides 3 cooperating with the fans. The fans are located on a shaft 4 which is driven at a constant speed by the delivery shaft 5 by means of a chain 6 or other positive drive. These two shafts are positively connected together to have a constant speed ratio. In this case I have shown it as fifty to eight because fifty products are to be delivered to form a bundle and there are eight fan blades shown. On the delivery shaft 5 are pulleys 7 for the delivery tapes 8. These tapes therefore work constantly and uniformly as usual.

On the delivery shaft 5 is fixed a ratchet wheel 9 having a number of teeth equal to the number of products to be delivered to form a bundle, fifty being shown. This wheel is keyed to the shaft. Loose on the shaft is a counter disc 10 having a notch 11 in its circumference for the purpose of pushing forward the last two or three products of a bundle to separate two bundles in the usual manner on the tapes.

Adjacent to the counter disc is a shaft 12 running across the machine and having thereon a cam lever 13 having a roller thereon and held up against the surface of the counter disc by a spring 14. This roller drops into a notch 11 shortly before a revolution is completed to swing the lever 13 and with it the counter toes 14^a which swing down into position to separate the products, as shown in Fig. 2, and as is usual in this class of machinery.

Pivotedly mounted on the disc 10 is a pawl 15 adapted to be pressed by a spring 16 into engagement with the teeth of the ratchet 9. This is the normal position of the parts,

as shown in Fig. 2. Obviously the rotation of the delivery shaft causes the counter disc 10 to rotate with it positively. The pawl 15 has a projecting arm 17 which is adapted to be engaged by a projection 18 on a link 19 if that link is in a certain position. In this case the pawl will be lifted, as shown in Fig. 3, back against a stop 20 and the shaft 5 can rotate a short distance without turning the counter disc, the purpose of which will appear hereinafter.

The link 19 is provided with a roller 21 which is capable of engaging the surface of the counter disc and rolling thereon and of moving down into the notch 11 therein to permit the projection 17 to start the operation just described. This link is connected at the top with a bell crank 22 keyed on a shaft 23. The other end of this bell crank 20 has a roller 24 adapted to engage a cam 25 fixed on the shaft 4 of the fan. This cam 25 is provided with a number of depressions and projections alternately arranged and equal in number to the number of fan blades, 25 eight being shown in the present case. Therefore if the roller 24 is allowed to come into contact with this cam 25, the link 19 would be raised by one of the projections and allowed to be lowered again any time a 30 fan blade moves through a space equal to one-eighth of the circumference. However, in normal action, the roller 24 does not engage the cam 25 because on the shaft 23 is an arm 26 adapted to be held down by a 35 spring 27 but normally held up out of operative position by a spring-pressed hand latch 28 as shown in Fig. 2. When held in this position the roller 24 is held away from the lower portion of the cam 25 and the roller 40 21 is also held up out of contact with the surface of the disc 10. Then the delivery will operate in its ordinary manner without any interference by this mechanism. That operation can be continued as long as desired.

On the shaft 23 is fixed a switch guide 29 to move with the shaft. In the position shown in Fig. 2 this switch guide is turned down out of the way so that it has no effect. 50 When the operator swings the latch 28 away from the arm 26 the spring 27 will depress that arm and bring the link 19 down so that the roller 21 thereon will rest on the surface of the counter disc 10. This throws the switch guide 29 up a little but not enough to divert the sheets. Now when the counter disc rotates far enough so that the roller 21 enters the notch 11 in its surface the spring 27, which has been under tension all 55 60 the time, will swing the shaft 23 and bring the link 19 down so that the projection 18 will be in the path of the rotating projection 17 and the latter will come into contact with it and raise the pawl 15 against the stop 20 65 at the same instant that the switch guide

29 is moved up into the position shown in Fig. 3 to divert a printed product on a table 31. At the same time the bell crank 22 swings with the shaft 23 and the roller 24 engages in one of the depressions in the cam 25. But this roll 24 cannot stay in that position any longer than the period required for a fan blade to move from one position, shown in Fig. 3, to the next, that is, long enough to receive a printed product and pass 75 out of receiving position. The next projection on the cam 25 will force the roller 24 outwardly to lift the link 19 and release the pawl 15. This also brings the arm 26 up over the end of the latch 28, the spring 80 32 of which will restore it to the position shown in Fig. 2, in which the parts of the throw-out are located in inoperative position.

The result of this operation is to provide 85 for the delivery of exactly the desired number of printed products on the tapes 8, no matter whether the operator manipulates the throw-out mechanism or not. In other words, the product of the machine will be 90 constant irrespective of the operation of the throw-out mechanism. The stoppage of the counting disc while one product is thrown out rectifies the counting. It will be seen also that the operator can release the latch 95 28 free from the position shown in Fig. 2 at any time. This is purely a hand function, but whenever he does it he has to hold the latch back until the roll 21 enters the notch 11 and the throw-out mechanism will 100 be held inoperative until it is automatically set into operation by the counter disc. Thus, the operator cannot control the exact time of operation of the throw-out mechanism. He can only select the particular 105 bundle which is to be finished before a product is thrown out and he can provide for throwing only one product out for each bundle delivered.

Thus the difficulty above explained which 110 has been universal heretofore, as far as I am aware, has been entirely avoided.

Although I have illustrated and described only a single form of the invention, I am aware of the fact that modifications can be made therein and that it can be used for other than printed products by any person skilled in the art without departing from the scope of the invention as expressed in the claims. Therefore, I do not wish to be limited to all the details of construction or to the kind of products operated upon, but what I do claim is:—

1. A delivery mechanism for printed products adapted to deliver a bundle of products and throw out one for inspection and provided with means for rectifying the count, so that each bundle will contain the full number of products desired in one bundle. 125

2. A delivery mechanism for printed prod- 130

- ucts having means for delivering the exact number of products required for one bundle, and means for throwing out an extra product for inspection without reducing the number in the bundle. 5
3. A printing press delivery having means for delivering the full number of products to form a bundle and provided with means for diverting a single extra product for inspection after the last product of the bundle has been started on its course through the delivery. 10
4. A delivery mechanism for printed products having means for delivering the exact number of products required for one bundle, and means for throwing out an extra product after enough products to form a complete bundle have been delivered or started through the delivery and before the first product for the next bundle is started through the delivery, and for interrupting the count to prevent counting the product thrown out. 15
5. In a delivery mechanism for printed products, means for counting out the products into lots containing a predetermined number of products, with hand controlled means adapted to rectify the count should a product be extracted from the stream of products passing to the delivery mechanism. 20
6. In a delivery mechanism for printed products, means for separating the products into lots or "bundles" containing a predetermined number of products, with means adapted to withdraw one or more products from the stream of printed products without lessening the number of products in any one lot. 25
7. The combination with a printing press delivery and counting device for separating the products delivered into equal bundles, of means arranged to be set into operation by hand for throwing out a product for inspection, and for preventing the inclusion of the product thrown out in the count. 30
8. The combination with a printing press delivery and counting device for separating the products delivered into equal bundles, of means for throwing out a product and for rectifying the count to ensure the delivery of the same number of products per bundle, whether the throw out mechanism is operated or not. 35
9. The combination with a printing press delivery and counting device for separating the products delivered into equal bundles, of means for throwing out a product and for arresting the operation of the counting device while the single product is thrown out without interrupting the operation of the delivery. 40
10. In a printing press delivery, the combination with means for delivering a predetermined number of printed products to form a bundle, of means for ejecting for inspection a single product timed to operate only after the exact number of products for a bundle have entered the delivery mechanism. 45
11. In a printing press delivery, the combination with a delivery fan and a delivery device for receiving the products from the fan and moving them along in evenly spaced overlapped relationship, of means for directing an extra single product from the fan and allowing the exact number of products to form a bundle to be delivered on the delivering device. 50
12. In a delivery of the character described, the combination with a rotary delivery fan, a delivery shaft positively connected therewith to rotate in a definite ratio thereto, delivery tapes connected with the shaft to be operated thereby constantly, and a counter having means for separating the products on the tapes into bundles, of means for periodically interrupting the operation of the count long enough to allow one product to be diverted from the fan. 55
13. In a delivery of the character described, the combination with a rotary delivery fan, a delivery shaft positively connected therewith to rotate in a definite ratio thereto, delivery means connected with the shaft to be operated thereby constantly, and a counter having means for separating the products into bundles, of means for periodically interrupting the operation of the count long enough to allow one product to be received by the fan, and means for simultaneously throwing out that product, whereby the count of the products delivered will be rectified. 60
14. In a delivery for printed products, the combination with a delivery fan, a counter disc, and means operated by the disc for separating the delivered products into bundles of equal numbers, of a delivery shaft to which the fan is geared, a ratchet wheel rotatable positively with said shaft, a pawl on the disc for engaging the ratchet and rotating the disc positively from the delivery shaft, a link having a roll adapted to engage the surface of the disc, the disc having a notch for receiving the roll at the end of a revolution, and means operated by the link when the roll is in the notch for disengaging the pawl from the ratchet wheel. 65
15. In a delivery for printed products, the combination with a delivery fan, a counter disc, and means operated by the disc for separating the delivered products into bundles of equal numbers, of a delivery shaft to which the fan is geared, a ratchet wheel rotatable positively with said shaft, a pawl on the disc for engaging the ratchet and rotating the disc positively from the delivery shaft, a link for disengaging the pawl from the ratchet wheel, hand operated means for 70
- 75

- 105
- 110
- 115
- 120
- 125
- 130

holding the link in inoperative position and releasing it, and means on the fan and on the shaft for causing the operation of the link to disengage the pawl except at certain 5 times.

16. In a delivery, the combination with a delivery fan, a delivery shaft, and delivery tapes operated by the shaft, of a count disc free on said shaft, a ratchet wheel fixed on 10 the shaft having a number of teeth equal to the number of products to be delivered to form a bundle, a pawl on the disc for engaging the teeth and positively driving the disc, and means operated by the disc for 15 throwing out an extra product as soon as the full number necessary for a bundle have started through the fan.

17. In a delivery, the combination with a delivery fan, a delivery shaft geared to rotate at a certain ratio to the speed of the fan, a ratchet wheel fixed on the shaft, a 20 counter disc free on the shaft having means for engaging said ratchet to rotate it therewith and having a notch, counter toes for 25 separating the products delivered into bundles, and means adapted to be operated by said notch for actuating the counter toes at the end of a complete revolution of the shaft, of means cooperating with, and 30 operated by, said notch for disconnecting the disc from the ratchet long enough to permit one product to be diverted from the fan without being counted by said counter disc and counter toe actuating means.

18. In a delivery for printed products, the combination with a delivery fan, a counter disc, and means operated by the disc for separating the delivered products into bundles of equal numbers, of a delivery shaft 40 to which the fan is geared, a ratchet wheel rotatable positively with said shaft, a pawl on the disc for engaging the ratchet and rotating the disc positively from the delivery shaft, a link for disengaging the pawl 45 from the ratchet wheel, hand operated means for holding the link in inoperative position and releasing it, yielding means for forcing the link into operative position, means on the disc for preventing the full action of the 50 yielding means except at the completion of a revolution of the shaft, and means operated by the fan for returning the link to inoperative position as soon as the delivery shaft has rotated through a space long enough to 55 permit delivering one product.

19. In a delivery for printed products, the combination of a fan, a counter disc, a cam rotatable with the fan, a lever adapted to engage the cam, the cam having depressions and projections adapted to move the lever 60 back and forth once each time the fan rotates through an arc sufficient to deliver or receive a product, a shaft on which said lever is fixed, a link connected to said lever 65 to be operated thereby, and means operated

by the lever for preventing the counter from operating during the time required for the entrance of one product into the fan so as to skip a count.

20. In a delivery for printed products, the 70 combination of a fan, a counter disc, a cam rotatable with the fan, a lever, adapted to engage the cam, the cam having depressions and projections adapted to move the lever back and forth once each time the fan rotates through an arc sufficient to deliver or receive a product, a shaft on which said lever is fixed, a link connected to said lever to be operated thereby, and means operated by the lever for preventing the counter from 80 operating during the time required for the entrance of one product into the fan so as to skip a counter, and a hand operated latch for normally holding the lever back out of the influence of said cam and out of operative position.

21. In a delivery for printed products, the combination of a fan, a counter disc, a cam rotatable with the fan, a lever adapted to engage the cam, the cam having depressions 90 and projections adapted to move the lever back and forth once each time the fan rotates through an arc sufficient to deliver or receive a product, a shaft on which said lever is fixed, a link connected to said lever to be 95 operated thereby, and means operated by the lever for preventing the counter from operating during the time required for the entrance of one product into the fan so as to skip a count, the counter having means for 100 preventing the link from operating and the lever from engaging the cam except at the time when the counter has counted out the full number of products to make a bundle.

22. In a delivery for printed products, the 105 combination of a fan, a counter disc, a cam rotatable with the fan, a lever adapted to engage the cam, the cam having depressions and projections adapted to move the lever back and forth once each time the fan rotates through an arc sufficient to deliver or receive a product, a shaft on which said lever is fixed, a link connected to said lever to be operated thereby, means operated by the lever for preventing the counter from 110 operating during the time required for the entrance of one product into the fan so as to skip a count, the counter having means for preventing the link from operating and the lever from engaging the cam except at 115 the time when the counter has counted out the full number of products to make a bundle, and a switch guide operated by the lever to direct a product from the fan when the counter stops.

23. In a delivery for printed products, the combination of a fan, a counter disc, a cam rotatable with the fan, a lever adapted to engage the cam, the cam having depressions and projections adapted to move the lever 120

back and forth once each time the fan rotates through an arc sufficient to deliver or receive a product, a shaft on which said lever is fixed, a link connected to said lever to be operated thereby, means operated by the lever for preventing the counter from operating during the time required for the

entrance of one product into the fan so as to skip a count, and a switch guide operated by the lever to direct a product from the 10 fan when the counter stops.

In testimony whereof I have hereunto affixed my signature.

HENRY A. WISE WOOD.
